UNITED STATES PATENT OFFICE.

WILLIAM GREENBERG, OF BRONX, NEW YORK, ASSIGNOR OF ONE-HALF TO EMIL KAUFMAN, OF BROOKLYN, NEW YORK.

DESIGN FOR A CLASP JAW FOR FUR SCARFS OR THE LIKE.

Application filed April 19, 1928. Serial No. 26,386. Term of patent 14 years.

To all whom it may concern:

Be it known that I, WILLIAM GREENBERG, a citizen of the United States, and a resident of the Bronx, New York, have invented a new, original, and ornamental Design for a Clasp Jaw for Fur Scarfs or the like, of which the following is a specification, reference being had to the accompanying drawing, forming part thereof.

Figure 1 is a bottom plan view of a clasp jaw for fur scarfs or the like, showing my new design, and

Figure 2 is a side elevation thereof.

I claim:

The ornamental design for a clasp jaw for fur scarfs or the like, as shown.

WILLIAM GREENBERG.
